W. F. RUHTER

RAILROAD SPIKE

Filed June 9, 1921

Inventor

William F. Ruhter

By *William J. Jacobie*
Attorney

UNITED STATES PATENT OFFICE.

WILLIAM F. RUHTER, OF JUANITA, NEBRASKA.

RAILROAD SPIKE.

Application filed June 9, 1921. Serial No. 476,259.

To all whom it may concern:

Be it known that I, WILLIAM F. RUHTER, a citizen of the United States, residing at Juanita, in the county of Adams and State 5 of Nebraska, have invented certain new and useful Improvements in Railroad Spikes, of which the following is a specification.

This invention relates to new and useful improvements in railroad spikes, and more particularly to a fastening means therefor, and the primary object of the invention is to provide a spike having means whereby a locking pin or nail may be inserted therethrough to claw or bite the material in which 15 the spike is introduced, thus preventing casual displacement of said spike.

A further object of the invention resides in providing a spike with an arcuate channel terminating in the side opposite that to 20 which the head of the spike is directed, the entrance opening of the channel to be countersunk to receive therein the head of the nail to be introduced therein.

Still another object of the invention resides in providing a locking nail or pin which is previously dipped in paint, liquor or other material to resist corrosion.

With these and other objects in view my invention consists in the novel features of 30 construction, combination and arrangement of parts as will be hereinafter referred to and more particularly pointed out in the specification and claim.

In the accompanying drawing forming a 35 part of this application:

The figure is a sectional view through the tie showing the spike in part section.

In describing the invention I shall refer to the drawing, in which 1 designates a railroad spike of the usual or any preferred 40 type adapted for introduction to a tie or the like 2. It will be understood that while I have shown a railroad spike for use in connection with railroad ties that this spike might be used for any other purpose and in connection with any other member than a tie, if desired.

The shank of the spike is provided with 45 an arcuately designed channel or keyway 3, coated with anti-corrosive material the open-

ings thereof terminating in the same face of the spike, such face being opposite that to which the head of said spike is directed. The upper opening of the keyway or channel, designated as 4, is countersunk. A nail 55 or key 5 is provided which is adapted to be introduced into the keyway 3 and the head of this nail or keyway will be seated in this countersunk portion 4. It will be seen that by driving a nail or key through the keyway, the end of said nail or key will be driven diagonally through the material into which the spike 1 is disposed to claw said material and prevent casual displacement of the spike. I prefer to first dip the nail or 60 key 5 into a liquor, paint or other material to coat the same and prevent corrosion.

From the foregoing description of the construction of my improved device, the 65 operation thereof will be readily understood, and it will be seen that I have provided a simple, inexpensive and efficient means for carrying out the objects of the invention.

While I have particularly described the 70 elements best adapted to perform the functions set forth, it is obvious that various changes in the form, proportion, and in the minor details of construction may be resorted to without departing from the spirit or sacrificing any of the principles of the 75 invention.

Having thus described my invention, what I claim is:

A spike having a shank and a head thereon, said shank being provided with an arcuate keyway in the upper half thereof, the crown of said arcuate keyway being in the plane of the vertical axis of said shank and the ends of said keyway being in vertical alignment in the one face of said shank 80 opposite that to which the head of said spike is directed, the upper terminal end of said keyway being enlarged and beveled outwardly, and a coated nail adapted to be introduced through said keyway, the head of said nail being adapted for seating in the enlarged end of the keyway, as and for the 85 purposes described.

In testimony whereof I affix my signature.

WILLIAM F. RUHTER.
